UNITED STATES PATENT OFFICE.

WILLIAM MCCLOSKEY, OF WINDSOR, CANADA, ASSIGNOR TO THE MCCLOSKEY WIRE FENCE COMPANY, LIMITED, OF SAME PLACE.

DEVICE FOR MAKING WIRE FENCES.

SPECIFICATION forming part of Letters Patent No. 630,465, dated August 8, 1899.

Application filed April 4, 1899. Serial No. 711,758. (No model.)

To all whom it may concern:

Be it known that I, WILLIAM MCCLOSKEY, a citizen of Canada, residing at Windsor, in the county of Essex and Province of Ontario, Canada, have invented a new and useful Device for Making Wire Fences, of which the following is a specification.

This invention relates more specifically to a hand-tool for weaving stay-wires to the line-wires of a wire fence; and the invention consists in the peculiar construction of a twister-wheel and of the supporting-frame, all as more fully hereinafter described, and shown in the accompanying drawings, in which—

15 Figure 1 is a perspective view of my improved device. Fig. 2 is a plan view thereof. Fig. 3 is a perspective view of the twister-wheel detached. Fig. 4 is a perspective view of the end of the supporting-arm of the twister-wheel, and Fig. 5 is a section on line $\alpha\alpha$ in Fig. 2.

In the drawings, A is the twister-wheel, B the drive-wheel, and C the handle for imparting motion thereto, the drive-wheel and twister-wheel having intermeshing bevel gear-teeth. These wheels are supported by an open-sided frame, which has two of its sides D E inclined toward each other, the other side F connecting them at the ends which are 30 farthest apart. The side D forms the hand-grip by means of which the operator holds the device, and it is provided with a suitable guard G for protecting the hand against accidental contact with the drive-wheel.

35 The drive-wheel B is secured to the end of a shaft H, which is journaled in the side D of the frame and carries at its free end the handle C.

The side E of the frame is formed on its 40 face with a longitudinal recess I and has formed near its free end a stub J, upon which the twister-wheel is journaled by means of a hub K, formed thereon. The twister-wheel and its hub are formed with a radial slot M, which is adapted to register with the recess I in the frame when the parts are in the position shown in Fig. 1.

The twister-wheel is formed slightly convex on its face and has a peripheral flange L, 45 which, in connection with a shoulder N on the stub J, prevents the twister-wheel from

losing its engagement with the drive-wheel. In Fig. 2 this flange is shown in a modified form by being provided with a rim W, and the guard G has a projection Y, which extends under said rim. In this manner the twister-wheel cannot by any possibility lose its engagement with the drive-wheel, as might possibly happen when the device is pulled off the line-wire after the operation. 60

O is the spool which carries the coiled-wire stay. This spool is preferably cast integral with the twister-wheel and is hollow and formed with a longitudinal slot P, through which the free end of a tension-spring Q, secured within the spool, is adapted to press against the coils of the wire, and thereby create the necessary tension, but any other means for producing this result may be employed. 70

R is an opening in the twister-wheel which forms the passage for the stay-wire from the spool to the line-wires in weaving.

S is a lug projecting from the face of the twister-wheel adjacent to the wire-passage R 75 for the purpose of guiding the stay-wire in twisting it around the line-wires.

T is a support formed with the open wire-passage U, by means of which the device is supported in position on the line-wire in 80 weaving. This support is formed with a loop V, adjacent to the handle when the latter is in the position as shown in Figs. 1 and 2.

In practice the stay-wire is first formed into coils of sufficient length for one or more 85 stays. A coil being placed upon the spool, the inner end is then pressed through the opening R, and in commencing to weave it is first twisted around the top line-wire. Then the device is applied to the line-wire next below, 90 as in Fig. 1, so that the line-wire passes loosely through the wire-passage U, recess I, and the inner end of the slot M in the twister-wheel. By giving the handle C then one turn the stay-wire is wrapped around the line-wire one 95 turn and the operator having hold of the device at the grip D pulls it out of engagement with the line-wire and repeats the operation at the line-wire next below, and so on to the last one. 100

The operation of weaving with my device is accomplished much more expeditiously

than with such tools which have to be bodily turned around the line-wire and it is also accomplished with an expenditure of less power.

A particular advantage of my device is that the grip D, by means of which the operator manipulates the tool, is substantially in line with the fence. Thus in disengaging the device from the line-wires after the twist is made he can apply his power to the best advantage, and thus the manipulation of the tool is much easier and less tiresome than in devices where the hand-grip is at right angles or nearly so to the fence. On the other hand, by placing the sides D E at a slight angle, as shown, it will be seen that the wheels A B can be made of relatively small diameter, while at the same time there is room for the handle C at the other end to turn around without danger of the operator hurting his hand on the line-wires.

By supporting the twister-wheel on a shaft directly in line with the arm E of the frame friction is reduced to a minimum, while at the same time the device is made compact and of simple construction.

By forming the loop V in proximity to the handle the operator is also enabled, by slipping his finger into this loop after giving the handle one turn, to hold the twister-wheel in the necessary alinement with the recess I to disengage it from the line-wire and readily reengage it with another.

What I claim as my invention is—

1. A device for securing stay-wires, comprising two members D and E inclined at a slight angle toward each other, one of said members forming a grip and the other a guide for the wire, and a drive-wheel B and twister-wheel A supported by the converging ends of said members D and E, as set forth.

2. A device for securing stay-wires, comprising two members D and E inclined at a slight angle toward each other, one of said members forming a grip and the other provided with a longitudinal recess to receive the wire, an end bar F uniting said members and holding them in proper position, and a drive-wheel B and twister-wheel A supported by the converging ends of said members D and E, as set forth.

3. In a device for securing stay-wires the combination of the open-sided supporting-frame formed with the side bar D, carrying the drive-wheel B, and with the side bar E carrying the intermeshing twister-wheel A, said side bar E having a longitudinal recess

to receive the line-wire and a stub J, upon which the twister-wheel is journaled.

4. A device for securing stay-wires, comprising two members D and E inclined at a slight angle toward each other, and a drive-wheel B and slotted twister-wheel A supported by the converging ends of said members D and E, one of said members forming a grip and the other having a longitudinal recess adapted to align with the slot in said twister-wheel, substantially as described.

5. A device for securing stay-wires, comprising two members D and E inclined at a slight angle toward each other, a drive-wheel B and a twister-wheel A gearing together and supported on the ends of said members, one of said members forming a grip and provided with the guard G between said grip and the meshing wheels A and B, substantially as described.

6. A device for securing stay-wires, comprising two members D and E inclined at a slight angle toward each other, one of said members forming a grip and the other a guide for the wire, and a drive-wheel B and twister-wheel A supported by the converging ends of said members D and E, the said wheel A having a slot extending to the center thereof and formed with a convex face, and a lug projecting from said convex face adapted to guide the stay-wire in twisting it around the line-wire, substantially as described.

7. In a device for securing stay-wires the open-sided supporting-frame formed with the side bar D carrying the bevel gear-wheel B, and with the side bar E having the stub-shaft J carrying the twister-wheel and having a shoulder N, and a flange L on the twister-wheel.

8. In a device for securing stay-wires the combination of the open-sided frame formed with side bars D, E, carrying the gear-wheels, the end bar F uniting the side bars, and the support T on said end bar formed with the loop V.

9. In a device for securing stay-wires the combination with the open-sided frame carrying the drive-wheel and twister-wheel, of the rim-flange W on said twister-wheel, and the fixed projection Y on the frame, coacting with said rim-flange W.
